UNITED STATES PATENT OFFICE.

HERBERT H. STEELE, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed May 16, 1924. Serial No. 713,641.

This invention relates to line-spacing for typewriting machines in which the normal or standard line-spacing unit may be minutely increased or diminished at will for 5 a predetermined line-space unitary dimension of greater or less degree, and to provide for multiples of that predetermined unit.

The principal object of the present invention is to provide an improved approximately universal line-spacing mechanism that can be adapted by a single adjustment to different permanent spacing units associated with any type-face-area employed in 15 a modern typewriting machine, and having suitable connections that automatically provide full or fractional multiples of any such desired spacing-unit in the ratio of 1 1/2, 2 1/2 and 3 line-space dimensions.

Another feature of the invention is in the provision of a platen that may be turned by hand in either direction to an unlimited extent, with a line-spacing mechanism connected thereto by a positive clutch element 25 comprising toothed members that are brought into co-operation at the initial movement of the line-space lever, and interlock in such a manner as to promote a positive transmission of movement between the line-space lever and the platen, thus providing for uniform line-space distances regardless of any abuse the line-space lever may be subjected to.

Another feature provides that a standard 35 unit of line-spacing may be readily changed to a unit of greater or less degree to register a predetermined spacing unit for the work-sheet, and, when once set, any subsequent line-space movement may be made 40 through the manipulation of the line-space lever in the usual manner.

Another feature provides that when a standard single line-spacing unit has been increased or reduced to a predetermined 45 spacing unit on the work-sheet, this single space dimension may be increased in multiples of 1 1/2, 2, 2 1/2 and 3, through the adjustment of a single part to an index-setting.

During the line-feeding motion of the 50 platen, it is positively connected to the line-spacing handle or lever, and said lever is provided with a stop mechanism for determining the length of stroke of the platen.

One element of this stop mechanism is the

lug on the carriage frame against which the lever normally rests, and the co-operative element of the stop mechanism for limiting the stroke of the lever and the platen comprises two stop devices, each of which is 60 independently adjustable. The function of one of the adjustments is to secure minute variations in the length of the line-spacing unit. The function of the other adjustment is to determine how many of such units 65 shall constitute a feeding movement of the platen in a line-space direction.

Usually on typewriting machines the line-spacing unit is invariable, and it is also usual for the line-space regulator to determine whether the platen shall revolve through 1, 2 or 3 of said invariable units. In the present instance, the unit itself is minutely variable, and provision is made of a regulating device which is settable to determine not only whether the platen shall 70 revolve to the extent of 1, 2 or 3 units at its line-feeding movement, but also gives it a capacity for revolving 1 1/2 or 2 1/2 units 75 at such movement.

As before said, the platen lever normally rests against a fixed stop, and to co-operate therewith to measure the extent of revolution of the platen, there is provided a minutely variable device to determine the 80 length of the unit, and also a regulating device to determine how many units shall compose a feeding movement of the platen.

The minutely variable stop in the present invention may be mounted directly upon the carriage frame, and may comprise a stop and a minute adjustment therefor. The line-space regulator may comprise a device settable to different positions along the carriage lever, and constructed to engage 90 said minutely adjusted stop at the completion of the lever stroke. The nearer said regulator is set to the fulcrum of the lever, the longer is the stroke of the lever and the platen. The more remote said stop is 100 set from the fulcrum of the lever, the shorter the lever stroke and the platen stroke.

The device on the lever is illustrated preferably in the form of a shackle which is settable to different positions on the lever, preferably by inserting a pin thereof into any selected hole in a series which extends the length of the lever, these holes being appropriately spaced. The end of this shackle is adapted to engage the minutely adjusta- 110

ble stop at the completion of the drive stroke of the lever. The shackle and the adjustable stop may be telescopically connected, so that the shackle may constitute something having the form of a plunger guided or telescoping in a sleeve and adapted to abut against the minutely adjustable stop; this telescoping device being pivotally connected by the shackle to the line-space lever, and being pivotally connected to the carriage frame, so that it has the form of an extensible link, thus conducing to simplicity, effectiveness and compactness, and minimizing the cost. The minute adjustment of the stop may be effected by a threaded cap upon the extensible link.

It will thus be seen that the shackle may be detached from the line-space lever and reattached thereto at any desired hole in the series, and that the extensibility of the link permits such attachment and also accommodates the variations in the length of stroke imparted to the shackle by the line-space lever. The shackle may comprise a tongue element which has the form of a plunger to fit in the sleeve of the minutely adjustable stop element. While these and other parts are illustrated in one form in the drawings, still it will be understood that the invention includes reversals of parts and other variations.

Other features and advantages will hereinafter appear.

In the accompanying drawings, Figure 1 is a full size elevational view of the left-hand end of a typewriting machine carriage constructed and arranged according to this invention.

Figure 2 is a plan view of the extreme left-hand end of the carriage, showing the line-spacing devices arranged in operative position.

Figure 3 is a vertical sectional view taken on a plane indicated by the line 3—3 in Figure 2.

Figure 4 is an enlarged detail view of the spring-pressed detent connecting the line-space lever to its adjustable stop.

Figure 5 is an enlarged longitudinal section illustrating parts associated with the minute adjustment of the line-space lever stop.

Figure 6 is a detail view, showing the long roller that co-operates with the line-space lever at the two shift positions of the carriage.

Figure 7 is a diagrammatic view, showing the transmitted movements of the pivotal points on the line-space lever.

Figures 8, 9 and 10 are enlarged sectional views illustrating the manner of controlling the interlocks between the line-spacing transmission and the platen.

Figure 11 is a transverse sectional view taken on the line 11—11 of Figure 8.

Figures 12 and 13 illustrate a modification in construction of the means for controlling the operation of the interlocking dogs in transmitting movement of the line-space lever to the platen.

Figure 14 is a transverse sectional view taken on the line 14—14 of Figure 8, looking in the direction of the arrow.

Figure 15 is an enlarged plan view of the crown wheel associated with the clutch elements, illustrating the relative position of the three dogs that co-operate with the teeth thereof.

Figures 16, 17 and 18 are diagrammatic views, indicating the operation of lowering the dogs from their normal or raised position, to their lower or operative position in engagement with the teeth of the crown wheel, and for purposes of illustration the dogs are shown in these three figures diametrically opposite each other.

Referring in detail to the drawings, the usual Underwood cylindrical platen 20 is mounted upon a shaft 21 journaled in a platen frame 22 carried by a traveling carriage frame 23, and is shiftable up and down to agree with the upper and lower case faces of type on type-bars 24. The platen is also provided with feed-rolls 25 adapted to feed the work-sheet around the platen from the rear in the well-known Underwood manner.

The platen 20 is line-spaced to feed the work-sheet by a novel mechanism including a line-space lever 26 pivoted to a shoulder screw 27 usually threaded into a lug on the carriage frame 23, the line-space lever swinging between lugs 28 and 29 forming part of the frame 23, the lever normally resting against the lug 28 which serves as the initiating gage for the length of the lever stroke.

The lever 26 is provided with a crank-arm 30, adjustably secured to it for facilitating assembly and having at one end an open slot to engage with a roller 31 pivoted between flanges 32 formed at the forward end of a driver in the form of a slide 33 arranged for reciprocation, the length of the roller 31 being sufficient to engage with the arm 30 in both upper and lower shift positions, it being understood that when the platen and platen frame shift to upper case position the slide 33 shifts up therewith, inasmuch as said slide is mounted on the platen frame while the crank-arm 30 remains stationary on the carriage frame.

The slide 33 is guided by slots 35 through which pass shoulder screws 34 fixed in the frame, and the slide at its rear upper edge is flanged as at 36 and formed with rack-teeth 37 to drive a pinion 38. The connections between the pinion 38 and the platen 20 which cause the platen to advance when the lever 26 is moved to the right of Figure 2, include a spiral pinion and a spiral gear,

the advance of the platen being in proportion to the extent of lever movement, but the platen remains idle during return movement of the lever.

5 The extent to which the line-space lever 26 may be moved in a line-spacing direction is controlled by two separate factors that operate independently and in unison, one factor operating to vary minutely the 10 extent of the line-spacing unit, and the other factor operating to multiply that unit. The unit varying elements may comprise a telescopic link or shackle including in one form a plunger or rod 40 sliding freely within a 15 sleeve 41 supported on a pivot 42 carried by a bracket 43 on the front rail of the carriage frame 23. One end of the sleeve 41 is internally threaded as at 44 to receive a threaded stud 45 riveted to the inside of a thimble or 20 cap 46 movable freely on the sleeve 41.

In Figures 1, 2 and 4 the numeral 47 indicates a detent pin mounted at the free end of the plunger rod 40 and provided with a button 48 to retract the pin, and a spring 49 25 to restore it. To co-operate with this pin 47 the line-space lever 26 is provided with detent openings 50, and by entering the pin 47 into any one of these openings the pin 30 becomes a pivot for the plunger rod 40, and the extent of movement of the line-space lever 26 is limited by the abutment of the end of the plunger 40 with a corresponding end of the stud 45; hence by arranging the 35 openings 50 at predetermined radial distances from the pivoted axis 27 of the line-space lever, various ratios of line-space distances may be provided for with a fixed stop position for the line-space lever. This feature is illustrated diagrammatically in Figure 40 7, in which the numeral 51 indicates a stop position when the plunger 40 strikes the stud 45, and the line X indicates the distance from the point 51 to the center of the pin 47; hence the stop position of the pin 47 45 at the end of any stroke of the line-space lever will intercept the radial line X, and the relation of X to Y will always be the same for any setting of the screw stud 45.

50 By moving the stop position 51 forward from a fixed zero position on the sleeve 41, the line Y will be advanced towards the line-spacing movement to check the stroke of the line-space lever, or said line Y will 55 be drawn to the right of Figure 2 and increase the effective stroke of the line-space lever.

The adjustment of the stop stud 45 determines the length of the line-spacing unit, and to produce means for indexing this movement the sleeve 41 may be provided with a scale 52, each line thereof indicating a full revolution of the thimble 46 which may be graduated as at 53. If the threaded elements 44 and 45 have a screw pitch of 60 forty threads to the inch, and the thimble 65

46 is graduated by twenty-five equally spaced lines, it will be possible to set the position of the point 51 to multiples of .001 of an inch.

For the purpose of illustrating this invention, a standard cylindrical platen is employed with a standard single line-space dimension of .167 of an inch, but it will be understood that other dimensions and ratios may be used with equal success. The zero 70 setting of the thimble 46, see Figure 2, indicates a line-spacing unit of .167 of an inch when the index pin 47 is set within the hole "a" of the line-space lever, shown at Figure 7. If said thimble 46 is turned forward 75 upon the sleeve 41 to an index reading of .009 the line Y will be advanced .009 inches, and the effective length of the line-spacing unit will be reduced to the difference between .167 and .009 which gives .158 for a 80 single line-spacing unit.

Similarly, if the thimble 46 is turned in the opposite direction the line Y will withdraw a distance of .009, and the effective 85 length of the line-spacing unit will be 90 lengthened .167 inches, and this dimension will be conveyed to the roller 31 and the slide 33.

As already set forth, the line Y indicates the 95 stop position for the holes 50 in the line-space lever and the predetermined multiples of line-spacing units made for the purpose of illustration of 1-1/2, 2, 2-1/2 and 3. These multiples of .167 for a single space unit may be indicated for the position of the roller 31 to transfer these ratios, and these roller positions transferred to the line-space lever 26 on the opposite side of the pivot 27, while the values of the radial lines 100 that intercept the holes a, b, c, d and e have the same values as the multiples of movement for the roller 31, and hence when the line-space lever 26 is moved to the right of Figure 2 to the broken line position marked "2", the index pin having been previously 105 set within the opening "c" in the line-space lever, the plunger 40 will move from the dotted-line position in Figure 5 to the full-line position of the same figure, and the transmitted movement of the roller 31 will 110 convey a double line-space movement to the surface travel of the platen of .333 inches.

115 In a like manner, by raising and re-setting the pin 47 in any one of the openings a, b, c, d or e, predetermined multiples of any 120 predetermined line-spacing units will be automatically provided for by this simple operation of changing the index position relative to the line-space lever.

125 As shown at Figure 8, the pinion 38 has a pivot 57 on one side, and a spindle 58 on the other side mounted in brackets 59 and 61 secured to the carriage-end. The under-side of the pinion 38 has a shouldered portion to which is firmly secured a disk 62 130

arranged to drive a second disk 63 mounted directly below it, loosely upon the spindle 58 by means of conical projections 64 on the underside of the disk 62 adapted to align 5 and nest within depressions 65 in the upper face of the disk 63. In place of the projections 64, pins 64^a may be substituted, as shown in Figures 13 and 14 to perform a similar function. These clutch controlling 10 disks 62 and 63 are arranged for a limited relative movement in a manner and for a purpose hereinafter more fully explained.

A floating ring 66 having a concave underside presents its flat upper surface to bear 15 against the underside of the disk 63 and its angular underside 67 to rest upon the bevelled faces 68 of the three dogs 69. These dogs 69 are arranged for a sliding movement within a cylindrical carrier 70 fixed to the 20 spindle 58, and are held in the carrier by a circularly shaped flat spring 71, set into an annular groove in the carrier and bearing against the upper edges of the dogs 69 in such a manner as to hold them in any position 25 by frictional engagement of the spring. The dogs 69 are equally spaced from each other around the carrier 70, and the lower ends of each dog are provided with a plurality of fine ratchet-shaped teeth.

30 Directly under the carrier 70 and separated by a slight clearance space is a clutch or toothed crown wheel 72, freely rotatable upon the spindle 58 and having fine teeth similar to the teeth of the dogs 69, but arranged in opposed relation, so that the teeth of the dogs, when brought to interlock with the teeth of the clutch, become driving elements to rotate the clutch in unison with the dogs in one direction only.

40 The clutch 72 has a tongue 73 across its lower end to interlock with a groove or slot 74 cut across the adjacent end of a spiral toothed pinion 75 to drive the same so that both may rotate in unison freely about the 45 spindle 58; the clutch is prevented from rising relatively to the pinion by a pin 55 set transversely in the spindle, the ends of the pin seating in a central recess 56 in the upper end of the clutch 72. The pinion 75 is in operative toothed driving relation with a companion spiral toothed gear secured to the platen shaft 21.

From this description, up to this point, it 55 may be seen that the platen may be rotated in either direction, by the finger-wheels 77 and during such rotation the gear 76 will drive the pinion 75 to rotate about its axis 58, and that any end thrust of the pinion 75 will be resisted by the pin 55 and the bracket 61; that movement of the line-space 60 lever to the right hand will cause the sliding rack 37 to rotate the pinion 38, the two disks 62, 63, the ring 66 and the dog-carrier 70 freely in unison but that no co-operative 65 movement takes place between these two sep-

arate devices because the dogs 69 are not in operative interlock with the clutch 72.

To effect co-operation of the dogs 69 and the clutch 72 the disk 63, which is free to turn on the spindle 58 except for the interlock of the elements 64 and 65, is provided with a brake or drag to check the free rotation thereof, consisting of the extension 78 of the bracket 61 which is concavely curved at its edge to serve as a shoe bearing under 75 tension against the edge of the disk 63.

The provision of a drag to resist a free turning of the disk 63 causes the conical projection 64, or the rounded edge of the pin 64^a in the disk 62 to ride up the inclined 80 face of the depression 65 in the disk 63, pressing the latter downwardly, and in turn carrying the ring 66 with it.

The ring 66, resting upon the bevelled upper ends of all three dogs 69, causes these dogs to move downwardly with the ring until further movement of individual dogs is checked by their coming into contact with the teeth of the clutch 72 at varying positions and, as already set forth, the dogs are 85 equally spaced about a circle, as shown diagrammatically at Figure 15, and the number of teeth on the clutch 72 being an even number, the three dogs differentiate from the teeth of the wheel 72 as 1/3, 2/3 and 3/3 of the pitch of a single tooth, so that when one dog is in full tooth engagement with one tooth of the clutch the other two dogs have no operative engagement, and when two dogs have a partial tooth engagement the 90 third dog is inoperative as a driving factor.

This movement of the dogs 69 is shown diagrammatically at Figures 16, 17 and 18, and one dog is seen to have a full toothed engagement at Figure 13. Figure 16 shows the normal inoperative position; Figure 17 the position where the downward movement of the ring 66 brings the left-hand dog into engagement with the angular face of the adjacent tooth 72^a, while the right-hand dog has a further downward movement fully engaging with the tooth 72^b.

The full downward movement is shown at Figure 18 where both dogs bottom against the teeth of the clutch 72, and assume different planes relative to the face of the floating ring 66; hence continued pressure against said ring will force it to move transversely across the plane of the dogs and assume a position where it will engage with all three dogs and become an equalizing wedge-like element between the disk 63 and the upper ends of the dogs.

This movement of shifting the dogs 69 into operative relation with the clutch 72 takes place at the initial movement of the line-space lever, and is effected before the part 64 can be wholly withdrawn from the depression 65; hence when the interlock of the dogs 69 with the clutch 72 checks the 125 130

further downward movement of the disk 63, said disk is forced to rotate with the disk 62 and thus transmit continued rotation of the pinion 38 to the spiral pinion 75 and gear 76, to rotate the platen in a line-space direction.

On the initial return stroke of the line-space lever the disk 62 will move to the position shown at Figure 9, which releases the pressure on the dogs, and to prevent the projection 64 from riding up the opposite side of the depression 65 a pin 79 projects from the disk 62 to enter a hole 80 in the disk 63, and by reason of such engagement the pin will rotate the disk 63 in a direction reverse to the arrow in Figure 14 and maintains an inoperative position of the projection 64 relative to the depression 65.

When pressure is removed from the dogs 20 the initial return movement of the line-space lever and the dog carrier rotates in a direction reverse to the arrow of Figure 13, the angular faces of the teeth in the clutch 72 become camming elements to push 25 the dogs upwardly within the carrier until the teeth of the dogs are clear of the clutch teeth, the spring 71 frictionally holding all three dogs in this raised or inoperative position until the next line-spacing operation.

It will be noted that the platen has no detenting elements, common with most toothed line-spacing elements, it being assumed that the present invention, with the 35 various paper-holding devices associated with the platen, will promote sufficient drag to prevent any accidental rotation of the platen from a fixed setting determined by the line-spacing elements herein set forth. Should these elements, bearing against the 40 platen surface, prove inadequate to properly hold the platen stationary between line-spacing operations, a braking connection equivalent to the resistance of the usual 45 detent roller may be employed to hold the platen; one of such means comprises an extension 81 of the bracket 59 adapted to engage with the edge of the metal platen head 82 and provided with an adjusting 50 screw 83 threaded into the carriage ends to determine the degree of pressure of the brake against the platen head.

It will be noted as a conspicuous factor, 55 the absence of springs in the construction of this line-spacing mechanism. The circular flat spring 71 operates, not to restore the dogs, but to exert a frictional contact to maintain them at one of two positions and cannot easily become ineffective. To restore 60 the line-space lever and its connections to the spindle 58, a single, comparatively strong spiral spring 84 is connected between a stud 85 on the slide 33 and a stud 86 on the carriage-end.

Variations may be resorted to within the 65 scope of the invention, and portions of the improvements may be used without others.

Having thus described my invention, I claim:

1. In a typewriting machine, the combination with a carriage having a frame, and a platen-carrying shaft revoluble therein, of a line-space lever for actuating said shaft, a sleeve supported by said frame to pivot in a horizontal plane, a rod slidable in said sleeve, means adjustable on said sleeve to limit the inward movement of said rod, and means on the outer end of said rod engageable with said lever.

2. In a typewriting machine, the combination with a carriage having a frame, and a platen-carrying shaft revoluble therein, of a line-space lever for actuating said shaft, said lever having openings located at different distances from its pivotal axis, a sleeve pivotally supported by said frame to oscillate in a horizontal plane, a rod slidable in said sleeve, a thimble adjustable on said sleeve, an abutment carried by said thimble to intercept the inner end of said rod, and means on the outer end of said rod engageable in any of the mentioned openings in said lever.

3. In a typewriting machine, the combination with a carriage having a frame, and a platen-carrying shaft revoluble therein, of a line-space lever for actuating said shaft, said lever having openings located at different distances from its pivotal axis, a sleeve pivotally supported by said frame to oscillate in a horizontal plane, a rod slidable in said sleeve, means on said sleeve to define the entry distance of said rod within the sleeve, and a spring-actuated detent pin carried at the outer end of said rod selectively engageable in any of the openings in said lever.

4. In a typewriting machine, the combination with a carriage having a frame, and a platen-carrying shaft revoluble therein, of a line-space lever for actuating said shaft, a micrometer pivoted on said frame, a bar slidable in the sleeve of said micrometer, its inner end abutting the screw of the micrometer and limiting the movement of said bar, a spring-pressed detent carried on the outer end of said bar, and an arcuate row of detent-receiving openings in said lever, each opening being a predetermined radial distance from the pivotal axis of the lever.

5. In a typewriting machine, the combination with a carriage having a frame, and a platen-carrying shaft revoluble therein, of a line-space lever for actuating said shaft, said lever having a plurality of openings, each opening being located at a definite radial distance from the pivotal axis of the lever, and means interchangeably engageable in any of the openings to define the action of

said lever when moved in platen-operating direction, said means being adjustable to a thousandth part of an inch.

6. In a typewriting machine, the combination with a carriage having a frame, a platen-carrying shaft revoluble therein, and a line-space lever, of a spiral gear fixed on said shaft, a spiral pinion meshing with said gear, said pinion normally driving the gear 10 and being susceptible of being driven by it, a finger-wheel rigid on said shaft for manually rotating the platen in either direction, and means actuated by said lever, including said pinion and gear, to rotate the platen, in line-spacing direction only, a finely adjustable degree.

7. In a typewriting machine, the combination with a carriage having a frame, a platen-carrying shaft revoluble therein, and a line-space lever, of a spiral gear fixed on said shaft, a spiral pinion meshing with said gear and normally driving the same, a finger-wheel fixed on said shaft to turn the platen in either direction irrespective of said gear and pinion, and means intermediate said lever and pinion operative to rotate the pinion in a direction to advance the platen in line-spacing direction through an arc of predetermined degree.

8. In a typewriting machine, the combination with a carriage having a frame, a platen-carrying shaft revoluble therein, and a line-space lever, of a slide movable rectilinearly across said frame at one end thereof, said slide having a rack incorporated therewith, a roller pivoted at the front of said slide, a plate adjustably mounted on said lever, said plate having a fork operatively engaging said roller to actuate the slide, means for accurately determining the distance through which said lever can be moved, a spur pinion meshing with said rack, a spindle formed on said pinion, a spiral pinion revoluble on said spindle, a spiral gear fixed on said shaft and meshing with the spiral pinion, and intervening means on said spindle to transmit rotary motion from said spur pinion to the spiral pinion to advance the platen in line-space direction, the last-named means becoming disengaged upon reverse motion of said spur pinion.

9. In a typewriting machine, the combination with a carriage having a frame, a platen-carrying shaft revoluble therein, and a line-space lever, of a finely-adjustable stop determining the angular movement that can be imparted to said lever, a slide movable rectilinearly across said frame at one end thereof, a rack incorporated with said slide, an adjustable connection between said lever and said slide, a bracket fixed on the carriage end frame, a spindle revoluble in the bracket, a spur pinion rigid on said spindle, said pinion meshing with said rack, a spiral pinion rotatable on said spindle, a positive

clutch operating automatically on said spindle to lock said spur pinion, when driven in one direction, to said spiral pinion and to release the spiral pinion upon reversal of motion, and a spiral gear fixed on said shaft 70 to mesh with the spiral pinion, whereby said platen is rotated through a predetermined arc in line-space direction at each full movement of said lever against its stop.

10. In a typewriting machine, the combination with a carriage having a frame, a platen-carrying shaft revoluble therein, and a line-space lever, of a finely-adjustable stop determining the angular movement that can be imparted to said lever, a slide movable 75 rectilinearly across said frame at one end thereof, a rack incorporated with said slide, an adjustable connection between said lever and said slide, a bracket fixed on the carriage end frame, a spindle revoluble in the 80 bracket, a spur pinion rigid on said spindle, said pinion meshing with said rack, a spiral pinion rotatable on said spindle, a clutch rotatable on said spindle and keyed to said spiral pinion, said clutch having ratchet-shaped teeth on its upper surface, a carrier fixed on the spindle adjacently above said clutch and having open longitudinal recesses in its periphery, dogs slidable in the mentioned recesses, said dogs having teeth at 90 their lower ends to engage the teeth of said clutch, resilient confining means for said dogs, means for pressing said dogs into engagement with the clutch teeth, the last-named means becoming operative coincidentally with initial movement of said spur pinion to impart rotation to said spiral pinion in one direction, and a spiral gear fixed on 95 said platen shaft and in mesh with the spiral pinion.

11. In a typewriting machine, the combination with a carriage having a frame, a platen-carrying shaft revoluble therein, and a line-space lever, of a finely-adjustable stop determining the angular movement that can 100 be imparted to said lever, a slide movable rectilinearly across said frame at one end thereof, a rack incorporated with said slide, an adjustable connection between said lever and said slide, a bracket fixed on the carriage end frame, a spindle revoluble in the 105 bracket, a spur pinion rigid on said spindle, said pinion meshing with said rack, a spiral pinion rotatable on said spindle, a clutch rotatable on said spindle and in engagement 110 with said spiral pinion, said clutch having a central recess in its upper face and radially disposed ratchet-shaped teeth thereabout, a carrier fixed on the spindle adjacent the clutch, said carrier having longitudinal recesses in its periphery and an annular groove, dogs slidable in the mentioned recesses, said dogs having teeth engageable 115 with the teeth of said clutch at their lower ends and being beveled at their upper ends,

- a spring ring set in the mentioned groove to make frictional contact with said dogs, a floating ring having a concave under surface resting on said dogs, means for exerting pressure on said ring at the inception of rotation of said spur pinion in an advance direction, and a spiral gear driven by said spiral pinion, said gear being fixed on the platen shaft.
- 5 12. In a typewriting machine, the combination with a carriage having a frame, a platen-carrying shaft revoluble therein, and a line-space lever, of a bracket fixed on the end of said frame, a spindle revoluble in said bracket, a spur pinion fast on said spindle, a slideable rack engaging said pinion, said rack being actuated by said lever, a spiral gear fixed on said platen shaft, a spiral pinion revoluble on said spindle and meshing with said gear, a clutch fixed to said spiral pinion, said clutch having ratchet-shaped teeth on its upper surface, a carrier fixed on said spindle and having spaced longitudinal recesses in its periphery, dogs slideable in the mentioned recesses, said dogs having teeth engageable with the teeth of the clutch and beveled at their opposite ends, a floating ring having a concave lower face resting on the beveled ends of said dogs, a 20 disk having a detent recess and seated on said ring, a second disk fixed on the lower side of said spur pinion to rest on the first-named disk, a detent carried by said second disk engaging the recess in the first-named disk, and driving means fixed in the upper disk to loosely engage the lower disk, whereby relative movement of the disks is permitted.
13. In a typewriting machine, the combination with a carriage having a frame, a platen-carrying shaft revoluble therein, and a line-space lever, of a bracket fixed on the end of said frame, a spindle revoluble in said bracket, a spur pinion fast on said spindle, a slideable rack engaging said pinion, said rack being actuated by said lever, a spiral gear fixed on said platen shaft, a spiral pinion revoluble on said spindle and meshing with said gear, a clutch fixed to said 40 spiral pinion, said clutch having an even number of radial ratchet-shaped teeth on its upper surface, a carrier fixed on said spindle having three uniformly-spaced recesses lengthwise in its periphery, dogs slideable in the recesses, said dogs having teeth on their lower ends to engage the teeth of said clutch, and being beveled at their upper ends, a spring band associated with said carrier to maintain said dogs in any position they may assume, a floating ring having a concave lower face seated on the beveled ends of said dogs, and means for applying pressure on said ring coincidentally upon the commencement of rotation of said spur pinion in one direction, whereby one of said 45 dogs is forced into engagement with the teeth of said clutch, said dogs being raised to a uniform height upon reverse rotation of said spur pinion.
14. In a typewriting machine, the combination with a revoluble platen and a line-space lever, of line-spacing mechanism including a pair of spiral gears actuated by the lever and connected to the platen to operate the same, and adjustable means for regulating the number of line-spaces to which the platen can be moved at each actuation of said lever.
15. In a typewriting machine, the combination with a revoluble platen and a line-space lever, of a platen-driving rack, a gear-actuated mechanism operated by said rack to rotate the platen, and including an automatic clutch operable in one direction and inoperative in a reverse direction, and adjustable connections between said lever and rack.
16. In a typewriting machine, the combination with a revoluble platen and a line-space lever, of a platen-driving rack moved reciprocatively by said lever, a pinion meshing with said rack, a spindle driven thereby, a ratchet-toothed clutch, a spiral pinion combined therewith, said clutch and pinion being revoluble on said spindle, a spiral gear fixed on the platen shaft, and slideable dogs driven by said spindle to engage said clutch when said lever is moved in one direction and to release the clutch upon the return of said lever to normal position.
17. In a typewriting machine, the combination with a revoluble platen, of a spiral gear fixed on the platen, a spiral pinion meshing with said gear, a line-space lever, means enabling said lever to drive said pinion and gear to line-space the platen, and micrometer-controlled means for adjusting the movement of said lever to effect minute variations in the line-space movement of the platen.
18. In a typewriting machine, the combination with a revoluble platen, of a spiral gear fixed on the platen, a spiral pinion meshing with said gear, a line-space lever, means enabling said lever to drive said pinion and gear to line-space the platen, micrometer-controlled means for adjusting the reciprocal movement of said lever to effect fine variations of arc length movement of the platen, and independent means for increasing such movement without changing the micrometer adjustment.
19. In a typewriting machine, the combination with a revoluble platen, of a spiral gear fixed on the platen, a spiral pinion meshing with said gear, a line-space lever, means enabling said lever to drive said pinion and gear to line-space the platen, micrometer-controlled means for adjusting the reciprocal movement of said lever.

to effect fine variations of the line-spacing unit of movement of the platen, and independent means for multiplying such movement by 1, 2, 3 or a mixed number intermediate.

20. In a typewriting machine, the combination with a revoluble platen, of a spiral gear fixed on the platen, a spiral pinion meshing with said gear, a line-space lever, means enabling said lever to drive said pinion and gear to line-space the platen, micrometer-stop mechanism for arresting said lever to determine the extent of the line-spacing are length movement of the platen, and independently adjustable means for multiplying the line-spacing movement twice, thrice or fractionally at will.

21. In a typewriting machine, the combination with a revoluble platen having a shaft, of a spiral gear fixed to the shaft, a spiral pinion meshing therewith, a dog-and-ratchet device for rotating the pinion, a carrier for the dogs in said device, a pinion to drive said carrier, a rack meshing with said pinion, a line-space lever connected to said rack, a stop having a micrometer adjustment and being pivotally supported on the frame of the machine, and means for pivotally engaging said stop to the lever at variable points to afford single, double or triple line-spacing of the platen and also to afford line-spacing movements of mechanically-determined intermediate extent.

22. In a typewriting machine, the combination with a revoluble platen having a shaft, of a spiral gear fixed to the shaft, a spiral pinion meshing therewith, a dog-and-ratchet device for rotating the spiral pinion, a carrier for the dogs in said device to drive said pinion, a spur pinion driving said carrier, a rack meshing with said spur pinion, a line-space lever connected to said rack, a multiplying regulator for said lever, and a micrometer stop combined therewith whereby fine fractional line-spacing effects may be produced by said platen.

23. In a typewriting machine, the combination with a revoluble platen having a shaft, of a spiral gear fixed to the shaft, a spiral pinion meshing therewith, said gear and pinion operating to retard but not prevent the rotation of the platen, a line-space lever, mechanism actuated by said lever for rotating said pinion, and means for adjusting the range of action for producing finely variable line-spacing on said platen.

24. In a typewriting machine, the combination with a revoluble platen-carrying shaft, of line-spacing mechanism for the platen comprising a spiral gear fixed on the shaft, a spiral pinion in mesh therewith, a line-space lever, and a rack-and-pinion device actuated by said lever to rotate the spiral gear when the lever is moved in one direction, said device becoming disengaged

by movement of the lever in an opposite direction permitting a sweeping rotation of the platen.

25. In a typewriting machine, the combination with a revoluble platen-carrying shaft, of line-spacing mechanism for the platen comprising a spiral gear fixed on the shaft, a finger-wheel on said shaft, a line-space lever, a spiral pinion meshing with said gear, said pinion being normally free to rotate in either direction, and intervening mechanism actuated by said lever for engaging and rotating said pinion a predetermined amount, such engagement taking place at the initial movement of said lever.

26. In a typewriting machine, the combination with a carriage having a frame, a platen-carrying shaft revoluble therein, and a line-space lever, of a telescoping link comprised of two members, one of said members being pivoted to said lever and the other to said frame, and a minutely-adjustable stop associated with the frame carried link member limiting the distance the lever carried member can be entered therein.

27. In a typewriting machine, the combination with a carriage having a frame, a platen-carrying shaft revoluble therein, and a line-space lever, of a telescoping link comprised of two members, one of said members being pivoted to said frame, a pivot on the other link member adjustably engaging said lever, a positive stop carried by one of said link members arresting the closing movement of the link, and means for finely adjusting said stop.

28. In a typewriting machine, the combination with a carriage having a frame, a platen-carrying shaft revoluble therein, and a line-space lever, said lever having a plurality of openings arranged at different radial distances from its pivot, of a telescoping link comprised of two members, one of said members being pivoted on said frame, a pivot carried by the other member engageable in any of the mentioned openings in the lever, a stop carried by one of said members to arrest the relative sliding movement of said members toward each other, and means for minutely varying the positions of said stop.

29. In a typewriting machine, the combination with a carriage-frame, a platen-shaft-carrying frame vertically shiftable therein, and a line-space lever, of a rack slideable across the platen-shaft frame, a relatively long roller pivotally mounted on said rack to engage said lever irrespective of the relative positions of said frames, and mechanism actuated by said rack to turn the platen through an arc in exact proportion to the angular movement of said lever.

30. In a typewriting machine, the combination with a carriage-frame, a platen-shaft-carrying frame vertically shiftable therein,

- and a line-space lever on the carriage-frame, of a rack mounted upon and slidable across the platen-shaft frame, means connecting said lever to the rack, said means permitting 5 the rack to be shifted with the carriage-frame and independently of said lever, and mechanism actuated by said rack to turn the platen in line-spacing direction through an arc determined by said lever.
- 10 31. In a typewriting machine, the combination with a carriage-frame, a platen-shaft-carrying frame vertically shiftable therein, and a line-space lever, of a rack slidable across the platen-shaft frame, a relatively 15 long roller pivotally mounted on said rack, an arm extending laterally from said lever, said arm having a fork engaging the roller and permitting raising and lowering of the shift-frame, and mechanism actuated by said 20 rack to turn the platen in strict accordance with the angular movement imparted to said lever when moved in line-spacing direction.
32. In a typewriting machine, the combination with a carriage having a frame, a shift-frame therein, a platen having a shaft 25 revoluble in the shift-frame, and a line-space lever, of mechanism actuated by said lever for turning the platen in line-space direction, comprising a spiral gear fixed on said 30 shaft, a spiral pinion meshing therewith, a normally-open one-way clutch engaging said pinion, a rack-and-pinion device directly operated by the lever to rotate the clutch when open, and means consequent upon initial 35 actuation of said lever in line-spacing direction to close said clutch and impart proportional movement to the platen.
33. In a typewriting machine, the combination with a carriage having a frame, a shift-frame therein, a platen having a shaft revoluble in the shift-frame, and a line-space lever, of mechanism actuated by said lever for turning the platen in line-space direction, comprising a spiral gear fixed on 40 the platen-shaft, a spiral pinion meshing with the gear, a one-way clutch member engaging said pinion, all of the foregoing elements including the platen being free to rotate in either direction, mating clutch members 45 normally out of engagement with the first-named member, a rack having a slip-joint connection with said lever, a pinion driven by the rack to rotate the mating clutch members, and means becoming operative 50 upon initial rotative movement of the last-named pinion to cause engagement of said clutch members.
34. In a typewriting machine, the combination with a carriage having a frame, a shift-frame therein, a platen having a shaft revoluble in the shift-frame, and a line-space lever, of mechanism actuated by said lever for turning the platen in line-space direction, comprising a spiral gear fixed on the 55 platen-shaft, a spiral pinion meshing with the gear, a one-way clutch member engaging said pinion, said clutch member having an even number of uniformly-spaced, radially-disposed, ratchet-shaped teeth, an odd number of slidably mounted clutch members arranged uniformly in a circle adjacent the first clutch member and having complementary teeth, whereby only one of the slidable members can fully engage the first member at one time, said slidable members being 60 raised when rotated in non-driving direction, due to the angle of their teeth, a single spring retainer for holding all of the slidable members in any position they may assume, said slidable members being beveled at their opposite ends, a concave ring floatingly engaging the beveled ends, a rack-and-pinion drive for said slidable clutch members actuated by the line-space lever, and means for applying pressure to said ring causing 65 clutch tooth engagement, coincidentally operative upon actuating said lever in line-spacing direction, the reverse movement of the lever operating to free the slidable members of the clutch.
35. In a typewriting machine, the combination with a carriage having a frame, a shift-frame therein, a platen having a shaft revoluble in the shift-frame, and a line-space lever, of mechanism actuated by said 70 lever for turning the platen in line-space direction, comprising a spiral gear fixed on the platen-shaft, a spiral pinion meshing with the gear, a one-way clutch member engaging said pinion, said clutch member having an even number of uniformly-spaced, radially-disposed, ratchet-shaped teeth, an odd number of slidably mounted clutch members arranged uniformly in a circle adjacent the first clutch member and having complementary teeth, whereby only one of the slidable members can fully engage the first member at one time, a rack-and-pinion drive for rotating the slidable members about the axis of the first-named clutch member, said drive being directly actuated by the line-space lever, and means coincidentally operative upon actuation of the lever for pressing said 75 slidable members uniformly against the first-named clutch member whereby one of the slidable members will effect driving engagement therewith.
36. In a typewriting machine, the combination with a carriage having a frame, a shift-frame therein, a platen having a shaft revoluble in the shift-frame, and a line-space lever, of mechanism actuated by said lever for turning the platen in line-space direction, comprising a spiral gear fixed on 80 said shaft, a spiral pinion meshing therewith, a normally-open one-way clutch having an essentially fixed member engaging said pinion, and slidable members movable relatively thereto, a rack-and-pinion device directly connected to said line-space lever and 85

arranged to rotate the slideable members of the clutch on the axis of the fixed member, a disk fixed on the pinion of the rack-and-pinion device, said disk having a projection, a second disk having a depression receptive of said projection, and means connecting between said disks permitting a slight relative rotary movement to effect engagement or

disengagement of the projection in the depression, said projection when disengaged operating to press said slideable members into operative relation with the fixed member of the clutch, and when disengaged to permit the slideable members to become inoperative.

HERBERT H. STEELE.
